DRUM CLEANING MACHINE

Asa S. Johnson, Paulsboro, N. J., assignor to
Socony-Vacuum Oil Company, Incorporated,
New York, N. Y., a corporation of New York

Application September 13, 1932, Serial No. 632,930

3 Claims. (Cl. 141—6)

When a steel drum or barrel, such as is used in shipping petroleum products, is returned for re-use, it is necessary to clean it inside, and this is commonly done by introducing, together with water and detergent material, a length of chain, and then reciprocating and rotating the drum to cause the chain to slide over the inner surfaces with a scouring action.

To facilitate cleaning by this method, machines have been used which are provided with means for holding a drum in either vertical or horizontal position, for rotating it about its longitudinal axis, and for reciprocating it in a generally horizontal direction along a straight or an arcuate path.

This invention relates to machines of the type in question. One object of the invention is to produce a machine of rugged and powerful construction, in which the reciprocating movements are controlled by swinging links which support the barrel and its carrier with a minimum of strain and of friction. Another object of the invention is to produce a machine which will impart to the drum a combination of reciprocating and tilting movements which has been found to be particularly effective in cleaning the bilge or longitudinal surface of the drum.

To the foregoing ends the invention consists in the machine hereinafter described, and illustrated in the accompanying drawings, as it is defined in the annexed claims.

In the accompanying drawings, Fig. 1 is a side elevation of a drum-cleaning machine embodying the present invention, with parts of the frame broken away to show the mechanism more clearly; Fig. 2 is an end elevation of the same machine, looking from right to left in Fig. 1; Fig. 3 is a partial side elevation, in section on line 3—3 in Fig. 2; Fig. 4 is a detail view in section of the line 4—4 in Fig. 2; Fig. 5 is a general plan view of the machine; and Fig. 6 is a detail sectional view on the line 6—6 in Fig. 1.

In the illustrated machine, a drum or barrel 10 which is to be cleaned is mounted within an oblong frame 11 which, together with the parts associated with it, may be designated as the "drum carrier". The drum is held in place by end plates 12 and 13, which are slightly recessed to fit the ends of the drum. The end plate 12 is fixed on a short shaft 14 journaled in the end of the carrier 11, while the end plate 13 is pivoted on the end of a stem 15, which slides but does not turn in a bearing in the carrier.

The sliding movement of the stem 15 is to permit the introduction and removal of the drum,

Parallel lever arms 16 are pivoted, at one end, to the stem 15 and connected, at their other ends, with the carrier through a link 17. To one of the arms 16 a long arm or hand lever 18 is attached, by which the operator may move the arms 16 and the stem 15 to raise the end plate 13 from the drum, or to draw it down tightly against the drum. To lock the drum in place, means are provided for retaining the lever arms 16 in the required position. For this purpose a stem 19 is arranged to slide through the end of the carrier and between the arms 16, and the stem is provided with a cross arm or lever 20 at its outer end, and with a nut 21 threaded on its inner end. The lever arm 20 may be swung to the position shown in the broken lines in Fig. 2, in which case it lies between the arms 16 and permits them to be moved outwardly. When the arm 20 is swung to the position of Figs. 3 and 5, however, it crosses the arms 16 and thus locks them in a position determined by the nut 21. This nut may be adjusted according to the dimensions of the drum upon which the machine is to operate.

The drum carrier is supported in a structure which may be designated as a cradle and which comprises an upright U-shaped member 22 spanning the carrier. At its ends this member is provided with pivot studs 23 and 24, upon which the drum carrier is pivoted at the mid points of its side members.

The cradle comprises a second U-shaped member 25 integral with the first, and diagonal members 26 at the sides rigidly connecting the members 22 and 25. The weight of the cradle, the drum carrier and the drum is supported by two links 27 which are provided, at their lower ends, with pivot studs engaging bearings in the sides of the cradle member 22. The upper ends of the links 27 are pivoted on a horizontal cross rod 29 connecting two stationary frame members 30 which support the several parts of the machine. In order that the angular position of the cradle may be controlled, a second pair of links 31 is connected to the rear part of the cradle member 25 by pivot studs 32, and the upper ends of the links 31 are pivoted on a cross rod 33 connecting the frame members 30.

The necessary reciprocating or oscillating motion is imparted to the cradle, the carrier and the drum by mechanism actuated by an electric motor 34. This motor is connected, through suitable gearing, with a power shaft 36 carrying two crank plates 35, and the crank pins 37 on the plates actuate two pitmen 38, of which the

forward ends are pivoted to the links 27 at points 39 intermediate their ends.

The relative dimensions of the parts are such that the rotation of the crank plates causes the links 27 to swing through substantially equal angles on either side of their vertical position, with the result that the forward part of the cradle, together with the carrier and the drum, are caused to move in a circularly curved path 10 extending in a generally horizontal direction but curved upwardly toward each end. While the links 31, as shown, are of the same length as the links 27, their upper ends are pivoted at a lower point, and the distance between the pivot 15 rods 29 and 33 is greater than that between the pivotal points 24 and 32. There is therefore produced a linkage such that the arc of motion of the links 31 is mainly in front of the vertical plane of the pivotal axis 33, so that the pivot studs 20 32 descend when moving to the left (as shown in Fig. 1) and rise when moving to the right. The result of this movement is a slight tilting of the cradle, the carrier and the drum, such that when the cradle is in its extreme forward or right 25 hand position it is tilted forwardly, as shown in Figs. 1 and 3, while at the opposite extreme of the reciprocating movement it is tilted in the opposite direction. This combination of horizontally reciprocating and tilting movements has 30 been found very effective, when the drum is in the position of Fig. 3, in causing the chain to traverse the inner surface of the drum from end to end.

In order that both the end surfaces and the 35 lateral or bilge surfaces of the drum may be cleaned, the machine is arranged to permit the barrel and its carrier to be moved to and held in either horizontal position, as in Fig. 3, or vertical position as in Figs. 1 and 2. Movement 40 from one position to the other is permitted by the pivotal mounting of the carrier on the studs 23 and 24, and the carrier is retained in the desired position by locking mechanism. At each 45 end of the carrier is a lock lug 40 perforated to receive lock bolts 41 and 45 slidably mounted in the members 22 and 25 of the cradle. As shown in Fig. 2, the bolt 41, which is spring pressed to operative position, is connected, through a lever 42 and a rod 43, with a hand lever 44 mounted 50 to turn loosely on the pivot stud 23. By movement of this lever the lock bolt may be retracted when the carrier is to be swung upon its pivots. The lock bolt 45 is similarly connected, through 55 means including a rod 46, with the hand lever 44, so that either bolt may be retracted by the same means.

During the operation of the machine it is necessary that the drum be rotated slowly to 60 permit engagement of the chain with all parts of its inner surfaces. For this purpose the shaft 14 which supports the end plate 12 is connected, by bevel gears 47, with a shaft 48 journaled on the carrier, and the shaft 48 is connected, through a chain 49, with a sprocket-wheel 50 turning loosely on the pivot stud 24. A ratchet-

wheel 51 is fixed to the hub of the sprocket-wheel 50 and cooperates with a spring-pressed pawl 52 which is mounted on a lever 53 pivoted loosely on the hub of the sprocket-wheel. A link 54 is pivoted at one end, to lever 53 and its other end is pivoted on a rod 55 extending between the links 31. In consequence of this arrangement the swinging movements of the links 31 cause rocking movements of the lever 53, and this movement, through the operation of the pawl, results in intermittent rotative movements imparted to the end plate 12 and the drum.

It will be apparent that the suspension of the reciprocating members upon depending links permits these parts, and the drum, to move with a pendulum-like motion, so that they may be actuated without shock or strain and with a minimum expenditure of power. This arrangement also permits the drum to be supported at a point near the floor on which the machine rests, so that handling of the drum is facilitated in introducing it into, and removing it from the machine.

The invention claimed is:

1. In a drum-cleaning machine, the combination of drum-holding means including a cradle with a rearwardly-extending part, a link pivoted, at its lower end, to the forward part of the cradle and pivotally supported at its upper end, mechanism for oscillating said link through an arc substantially equally divided by the line of 30 the link when vertical, and a second link pivoted, at its lower end, to said rearwardly extending part of the cradle, the upper end of the second link being pivotally supported at a point such that the oscillating movements of the second link are, for the most part, in front of the vertical position of said link.

2. In a drum-cleaning machine, the combination of drum-holding means for supporting a drum with its longitudinal axis in a generally horizontal position, power-operated oscillating supporting mechanism to which said drum-holding means is pivotally attached on a transverse horizontal axis and by which said axis is caused to move through an upwardly concave curved 45 path, and means, connected with said drum-holding means, for tilting the same upon said transverse axis, during each oscillation, in a direction to depress the advancing end of the drum.

3. In a drum-cleaning machine, the combination of drum-holding means for supporting a drum with its longitudinal axis in a generally horizontal position, a stationary frame, two pairs of links pivoted, at their upper ends, to said frame and pivoted, at their lower ends, to said drum-holding means upon two spaced transverse horizontal axes, and means for oscillating said links to cause forward and rearward oscillations of the drum-holding means through an upwardly concave arcuate path, the lower pivotal axes of said 60 pairs of links being nearer together than the upper pivotal axes, so that tilting movements are imparted to the drum-holding means in consequence of said oscillations.
